Patented Apr. 24, 1917.

FIG. 1.

FIG. 2.

Inventor

E. E. Brown

By

Mark Tracy, Attorneys.

UNITED STATES PATENT OFFICE.

ERNEST E. BROWN, OF CHICAGO, ILLINOIS.

KEY-GUIDE FOR KEYHOLES.

1,223,366.

Specification of Letters Patent.

Patented Apr. 24, 1917.

Application filed September 28, 1916. Serial No. 122,714.

To all whom it may concern:

Be it known that I, ERNEST E. BROWN, a citizen of the United States, residing at Chicago, in the county of Cook and State of Illinois, have invented certain new and useful Improvements in Key-Guides for Keyholes, of which the following is a specification.

This invention relates to an improved key guide for keyholes and has as its primary object to provide a device of this character which may be readily applied to a door or other object to be employed in connection with substantially any conventional type 15 of lock as now in common use for directing the key into the keyhole of the lock.

The invention has as a further object to provide a device of this character which may be formed as a unitary structure struck from 20 a suitable piece of suitable sheet metal.

And the invention has as a still further object to provide a guide of the character above set forth which will be simple in construction and which may be readily mounted 25 in position.

Other and incidental objects will appear as the description proceeds and in the drawings wherein I have illustrated the preferred embodiment of the invention and wherein 30 similar reference characters designate corresponding parts throughout the several views,

Figure 1 is a perspective view showing my improved guide in connection with a 35 conventional type of lock escutcheon.

Fig. 2 is a detail perspective view on a slightly enlarged scale showing the device detached, and

Fig. 3 is a sectional view more particularly illustrating the manner in which the device is engaged with a door or other object for holding the guide in active position.

In carrying out the invention, the device 45 is formed with an elongated body 10 bent longitudinally to provide inwardly sloping guide walls 11 at the junction of which is formed a key opening 12. Extending from the longitudinal edges of the body 10 are 50 lateral and outwardly projecting wings 13 which slope transversely and inwardly to the guide walls 11 of the body 10 and are bent to provide longitudinally sloping guide walls 14 inclining inwardly toward the key 55 opening 12 to correspond to the inclination of the guide walls 11. Projecting laterally

from each extremity of the body 10 are a plurality of attaching prongs or attaching elements 15 which are preferably spaced apart and taper toward their free ends. 60

As previously intimated, the device is preferably formed as an integral structure and may, as will now be clear, be struck from a suitable piece of suitable resilient sheet metal. The body 10 is of a length to 65 extend transversely of the escutcheon plate of a lock and in Figs. 1 and 3, I have shown such a plate at 16, this plate being provided with a keyhole 17. The device is seated against the plate 16 with the key opening 12 70 in the body 10 of the device arranged opposite the keyhole 17 and with the prongs 15 abutting the side edges of the plate to engage the door or other object to which the plate is secured, a door being conventionally 75 shown at 18 in Fig. 3.

It will thus be observed that the device may be easily and quickly mounted in position by simply forcing the prongs 15 into the door and when so mounted, a key directed against the guide walls 11 of the device will be guided thereby toward the opening 12 in the body 10 into the keyhole 17. In like manner, the longitudinally and transversely sloping guide walls 14 will also 85 act to direct the key toward the keyhole 17 so that a key may be easily and quickly inserted within the keyhole without the trouble ordinarily experienced in this regard. In this connection, it will be seen 90 that my improved guide provides an exceedingly desirable device for assisting in the location of the keyhole in the night-time. Furthermore, the device is of such nature that it may readily be employed in connection with substantially any conventional 95 type of lock as now in common use.

Having thus described my invention, what I claim and desire to secure by Letters Patent is:

1. A device of the character described formed from a single piece of material and including an elongated body provided intermediate its ends with a key opening with the inner face of the body forming guide 105 walls sloping from the ends of the body inwardly toward the said opening, there being laterally and outwardly directed guide wings formed on the longitudinal edges of the body with the said wings sloping transversely toward the body and sloping longitudinally toward the said opening 110

with the extremities of the body provided with laterally directed attaching members.

2. A key guide of the character described including an elongated body provided centrally with an opening and formed with guide walls sloping from the extremities of the body toward the said opening, guide wings carried by the body and flanking opposite sides of the opening, and laterally

directed attaching members carried by the extremities of the body, the body being disposed to embrace an escutcheon plate with the attaching members abutting opposite edges of the plate and with the opening in the body registering with the keyhole opening in the plate.

In testimony whereof I affix my signature.
ERNEST E. BROWN. [L.S.]
